UNITED STATES PATENT OFFICE.

WILLIAM H. BRITTON, OF PERU, INDIANA, ASSIGNOR OF ONE-HALF TO LEROY O. BOWMAN, OF PERU, INDIANA.

DOOR-LOCKING MECHANISM.

1,277,843.

Specification of Letters Patent. Patented Sept. 3, 1918.

Application filed May 25, 1917. Serial No. 171,022.

To all whom it may concern:

Be it known that I, WILLIAM H. BRITTON, a citizen of the United States, residing at Peru, in the county of Miami and State of 5 Indiana, have invented new and useful Improvements in Door-Locking Mechanisms, of which the following is a specification.

This invention broadly relates to door locking mechanism, and provides for the 10 locking of a door in a manner whereby the same cannot be opened by unauthorized persons without giving evidence of such fact, the mechanism being simple in construction, yet very efficient for the purpose 15 intended.

Other objects will appear as the nature 20 of the invention is better understood from the following detail description, when taken in connection with the accompanying drawings, the invention residing in the construction, combination and arrangement of parts 25 as claimed.

In the drawings forming part of this 30 specification like numerals of reference indicate similar parts in the several views and wherein:

Figure 1 is a side elevation of a car body showing the door in locked position with my invention.

Fig. 2 is an enlarged view of the forward 35 edge portion of the door, a portion being partly broken away to disclose a part of the mechanism.

Fig. 3 is a sectional view taken on line 35 3-3 of Fig. 2.

Fig. 4 is a similar view taken on line 4-4 of Fig. 2.

Fig. 5 is a detail view of the sliding locking bar.

Fig. 6 is a view of the actuating means therefor.

The mechanism forming the subject matter of my invention is herein shown in connection with a freight car door, but it is 45 desired to have it understood that its use is not limited in this connection, and that it may be used with other doors.

Referring to the drawings in detail A indicates the body of the car, B the door, 50 which is mounted in any suitable manner for sliding adjustment between the tracks C. The door B may be constructed from any suitable material, but is preferably made up of two metallic interfitting sections 10 and 11 respectively, which can be rigidly

secured together in any suitable manner. The front edge of the door is provided with a latch receiving opening 12, the latch element indicated at 13 projecting from the adjacent edge of the door opening, so that 60 when the door is slid to its closed position the latch element 13 is received within the opening 12. The latch element is preferably provided with a hook-like extremity, which extends upwardly, while the said element is 65 also pivoted for vertical swinging movement, a spring 14 being connected with said element for normally maintaining the latter elevated.

Arranged between the respective sections 70 of the door, is a sliding lock bar 15 of substantially rectangular formation in cross section, this bar being disposed in parallelism with the front edge of the door, and cut away as at 16, the cut-away portion 75 being normally disposed in a line with the opening 12. Secured to one of the door sections, is a plurality of spaced superimposed lugs 17, and a vertically disposed flange 18, which bridges the space between 80 the lugs, the said lugs and flanges defining with the forward edge of the section, a pocket for the reception of a coiled spring 19. The bar 15 has its upper end offset as at 20. The spring 19 has one extremity 85 bearing against said offset portion, and its opposite end against the uppermost lug 17, an arrangement whereby the bar 15 is normally depressed. When the door is moved to its closed position, the latch element 13 90 enters the opening 12 and cut-away portion 16, and by reason of the fact that the spring 14 exerts an upward pressure upon the latch element, while the spring 19 exerts a downward pressure upon the locking bar 15, the 95 latch element and locking bar are effectively maintained operatively associated with a view of holding the door in its closed position.

Secured to the same section of the door 100 that has the locking bar 15 mounted thereon, is a key actuated sliding bolt 21 which is disposed at a right angle to the locking bar 15 and adapted to be received within an opening 22 in said bar to lock the latter 105 against displacement. The door section is provided with a key-hole slot 23 for the reception of a suitable key when it is desired to manipulate the bolt 21 either to lock the bar 15 in active position, or to release the 110

same to provide for the sliding adjustment thereof.

A transverse shaft 24 is journaled in the door section with its ends projecting beyond the opposite sides of said section, and fixed upon the innermost extremity of the shaft is a link 25 normally disposed at a right angle with respect to the locking bar 15, the link being bifurcated as at 26 to receive a stud 27 projecting from a lug 28 forming part of the locking bar 15. This construction and arrangement of parts effects a sliding adjustment of the locking bar 15 when the shaft is rotated. Fixed upon the opposite extremity of the shaft 24 and arranged exteriorly of the door is a lever 29 normally disposed vertically, and when said lever is depressed, or in other words moved downwardly in an arc of a circle, the shaft 24 is rotated in the proper direction to elevate the locking bar 15 against the tension of the spring 19, with a view of disengaging the bar 15 from the latch element 13, so that the door can be easily moved to an opened position. Manifestly when pressure is removed from the lever 29, the spring 19 operates to depress the locking bar 15, thereby automatically returning the latter and its associated parts to normal position.

However when the door is in its closed position the lever 29 is vertically disposed in its normal position, and a hasp 30 swingingly mounted upon the door frame is arranged transversely to bridge, cover and conceal the key-hole slot 28. The hasp is slotted as at 31 to receive an apertured lug 32 projecting from the lever 29, and subsequent to the association of these parts a pin 33 supported from the door by means of a flexible element or chain 34, is passed through the lug 32 as shown in Fig. 1. The pin 33 manifestly maintains the lever 29 and hasp 30 relatively positioned in the manner illustrated in Fig. 1, and consequently the key-hole slot is concealed from view, and obstructed, while the lever 29 is held against movement. The pin 33 is provided adjacent one extremity, with a slot 35 through which a metallic seal 36 of any suitable construction which prohibits the removal of the key from the lug 32, without destroying the seal, and by reason of which fact the door cannot be opened by unauthorized parties without affording evidence of the fact.

In practice the door is locked in the manner described, and when it is desired to unlock the door, the seal 36 is broken, and the pin 33 removed from the lug 32, subsequent

to which, the hasp 30 can be separated from the lever 29. The key actuated bolt 21 is then retracted from the opening 22 of the locking bar 15, and by moving the lever 29 downwardly, the locking bar 15 is elevated and simultaneously moved out of engagement with the latch element 13. The door is then free to be moved to an opened position. While it has been stated that the door is made of metal, embodying two associated sections, it is to be understood that the door can be made from wood, in which instance the door can be properly mortised for the reception of movable elements of the mechanism such as are intended to be carried by the door.

While I have shown and described what I consider the preferred embodiment of the invention, I desire to have it understood that I do not limit myself to the precise construction shown, and that such changes may be resorted to when desired as fall within the scope of what is claimed.

What is claimed is:—

1. Locking means for doors comprising a vertically disposed locking bar mounted on the door for sliding adjustment, said bar having its opposite longitudinal edges cut away to provide openings, a latch element adapted to be received within one of said openings of the bar when the door is in closed position, yieldable means normally tending to move said bar and latch element toward each other, a sliding bolt arranged at a right angle to said locking bar and adapted to be received within the other of said openings, whereby said bar and latch element are effectively maintained operatively associated, and means for effecting a release of said parts subsequent to the retraction of said bolt.

2. Locking means for doors comprising a vertically movable locking bar mounted upon the door, said bar having its opposite longitudinal edges cut away to define openings, a latch element adapted to enter one of said openings when the door is in closed position, yieldable means operating to hold said element and bar operatively associated, a sliding bolt adapted to enter the other of said openings, a lever, a connection between said lever and one end of said bar for releasing the latter from said element, subsequent to the retention of said bolt, and means for locking said lever in its normal position.

In testimony whereof I affix my signature.

WILLIAM H. BRITTON.
